UNITED STATES PATENT OFFICE.

CLAY R. VINSON, OF TULSA, OKLAHOMA.

NAPKIN-DISPENSING DEVICE.

1,423,701.

Specification of Letters Patent. Patented July 25, 1922.

Application filed June 6, 1921. Serial No. 475,271.

To all whom it may concern:

Be it known that I, CLAY R. VINSON, citizen of the United States, and resident of Tulsa, county of Tulsa, State of Oklahoma, have invented a certain new and useful Improvement in Napkin-Dispensing Devices, of which the following is a complete specification.

This invention relates to dispensing machines and more especially to devices of this character for dispensing paper napkins for restaurant service, but, of course, is adapted for use in dispensing paper towels or other articles made up of material in sheet form and designed to be wound in a roll and torn off as required for use.

One of the objects of the invention is to produce a device of this character whereby the purchaser may conveniently obtain from a roll any desired quantity of paper napkin material without any handling of the roll or unnecessary wasting of the material, and with which a strip of napkin material folded once and then rolled into cylindrical form may be used, if found desirable. With a roll of paper of this character, the operator will unfold the napkin after removing it from the roll, and will then have a substantially square napkin.

A further object is to produce a device of this character, especially adapted to be secured to the rear edge of a counter, but within convenient reach of the patrons of a restaurant, and which will protect the unwound portion of the roll from all dust and dirt.

Another object is to produce a device which may be easily and quickly replenished and which has no intricate or complicated parts which will require frequent adjustment.

A still further object is to produce a device of this character of simple, strong, durable, efficient and inexpensive construction; and in order that it may be fully understood, reference is to be had to the accompanying drawing, in which:

Figure 1 is a perspective view, partly broken away, of a paper napkin dispensing device embodying the invention.

Figure 2 is a rear view of the device with a part of same removed to more clearly illustrate the invention.

Figure 3 is a section on the line III—III of Figure 2; and

Figure 4 is a perspective view of a strip 55 of the folded napkin material as it appears when torn from the roll.

In the said drawing, where like reference characters identify corresponding parts in all of the views, 1 is a right-angle shaped 60 support provided at its ends with downwardly extending legs 2, provided with openings whereby the support is adapted to be secured to a counter 3 or the like, through the instrumentality of a series of screws 4. 65

The legs 2 are provided with slots 5 which are adapted to register with openings formed in the ends of a cross-piece 7, said cross-piece being secured in adjustable relation with respect to the counter by means 70 of clamping bolts 8. It will be understood that the position of adjustment of the cross-piece 7 will be determined according to the diameter of the roll of paper and by the width of the counter to which the device is 75 secured. Cross-piece 7 is formed at its ends with a pair of downwardly and rearwardly extending arms 9, formed near their ends with vertical slots 9^a adapted to receive a supporting shaft or spindle 10 provided with 80 an operating handle 11, and on which is mounted a roll of paper napkin material 12 folded longitudinally (see Figure 4).

The paper drawn from the roll will pass 85 rearwardly and over a guide arm 13 secured in ears 13^a formed on the legs 2 near the lower ends thereof. The paper will then pass vertically upward over a guide rod 15 mounted between a pair of ears 16 formed on the support 1, as illustrated. 90

At the front edge of the horizontal portion of support 1, that is, the portion resting on the face of the counter, a vertically extending guard 17 is formed, provided with a pair of side members 18. 95

At a suitable point above the surface of the counter, member 17 is formed with a horizontal forwardly projecting portion 19, and sides 18 are formed on the side edges of such portion with right-angle shaped portions 20 which form guides for the reception of a part hereinafter described. 100

Secured in sides 18 and above portion 19 is a cross rod 21 on which is pivoted a for-

wardly projecting clamping jaw 22 provided at its ends with operating fingers 23, and normally adapted to be held elevated under the pressure of a pair of coiled 5 springs 24 mounted on rod 21. In operation, the clamping jaw will be swung downwardly and will reliably clamp and hold the paper against slippage by pressing it against a right-angle shaped jaw member 10 25 depending from member 19 (see Figure 3), in which position the paper will be torn along the line of the clamping jaws. In order that the paper may be prevented from moving rearwardly and withdrawing its 15 projected end from between jaws 22 and 25, a guide roller 26 is mounted on a substantially inverted U-shaped spring frame 27 secured on member 1, and so proportioned that it will give slightly to allow paper to 20 be pulled from the dispenser, but will immediately move rearwardly and clamp the paper against the inside face of a cover member, hereinafter described, when such pulling force is removed.

25 It will be understood that the paper will be fed over the guides, as shown in Figure 3, and out between the clamping jaws, and in order to protect such paper napkin material from dust and the like, a cover member 30 is provided, formed with a forward extension 29 adapted to be engaged in the guides 20 and overlie the jaw 22, and a downwardly extending portion 30 which will depend to a plane slightly below guide 35 rod 13 and thus efficiently protect the unrolled portion of the paper from dust and the like.

Portion 28 is provided with a pair of flanges 31 formed with notches 32 for engagement with pins 33 in sides 18 to lock the cover against accidental dislodgment, it being understood that the flanges will overlap the upper extremities of sides 18. Portion 30 is provided with side flanges 34 of 45 sufficient width to lie in substantially the same plane as the edge of the counter 4 (see Figure 3), and thus close the sides of the dispensing device from the entry of dust and the like.

50 Member 28 is also provided with a pair of vertical members 35 between which menus, announcements or other material for distribution to the patrons may be placed, and the rearmost of said members is formed 55 with a pair of projecting wings 36 at each side, the lower edges of which will abut the counter and form suitable backings for salt and pepper shakers, knives and forks, or other utensils for the use of the patrons.

60 In order to obtain a napkin, the customer will grasp the torn end of the paper material projecting from the jaws and will pull the desired quantity from the dispenser. He will then apply downward pressure on 65 one of the ears 23 which will firmly clamp

the paper against the jaw 25. The paper may then be torn along the line of the clamping jaws, and the jaw 22 will immediately return to normal or elevated position upon the removal of the downward pressure 70 on one of the ears 23 and the device will be ready for a second operation.

It will thus be apparent that I have provided a practical and efficient device for carrying out the desired objects of the invention, and while I have illustrated and described what I now regard as the preferred form of dispensing device for embodying the improved features, I desire to reserve the right to make all such changes 75 or modifications as may fairly fall within the scope of the appended claims.

I claim:

1. In a device of the character described, the combination of a horizontal support, an 85 angular supporting member secured to one edge of said support and projecting both above and below the same, means for suspending a roll of material from the lower projecting portion of said member, a cover 90 member applied to said supporting member and having means cooperating with the upper projecting portion of the latter to clamp the material while a portion is being torn therefrom, and guiding means between 95 the source of material and said clamping means and including means for preventing rearward movement of the material after a portion has been torn therefrom.

2. In a device of the character described, 100 the combination of a horizontal support, a right-angle shaped support secured to the edge thereof and having downwardly extending legs, a material-carrying member 105 adjustably secured to said legs, paper clamping means carried by said right-angle shaped support, guiding means between said source of supply and said paper clamping means, and a cover member adapted to be removably secured to said right-angle shaped support.

3. In a device of the character described, a horizontal support, a right-angle shaped support adjustably secured to the edge thereof and having downwardly extending 115 legs, material-supporting arms adjustably secured to said legs, a paper guide carried by the lower ends of said legs, a second paper guide carried by said right-angle shaped support in the horizontal plane of 120 said first support, paper clamping means carried by said right-angle shaped support above said horizontal support, a cover member removably secured to said right-angle shaped support, and a yielding roller carried by said right-angle shaped support and adapted for pressing the paper against said cover member to hold said paper from rearward movement.

4. In a device of the character described, 130

a horizontal support, a right-angle shaped support secured to the edge of said first support and having downwardly extending legs, material-supporting arms adjustably secured to said legs, a paper guide carried by the lower ends of said legs, a second paper guide carried by said right-angle shaped support in substantially the same horizontal plane as said first support, paper clamping means carried by said right-angle shaped support above said horizontal support, a cover overlying said paper clamping means, and a roller carried by said right-angle shaped support in position for engagement with the paper and preventing rearward movement thereof after a portion has been torn therefrom.

5. In a device of the character described, the combination of a support, supporting means for a roll of material adjustably secured to said support and below the same a downwardly depending fixed jaw, a second jaw pivoted for cooperative engagement with said fixed jaw to clamp the paper while 20 a portion is torn therefrom, guiding means 25 between the source of material and said

clamping jaws, and means for preventing rearward movement of the paper after a portion has been torn therefrom.

6. In a device of the character described, 30 the combination of a horizontal support, a right-angle shaped support adjustably secured to the edge of said first support and having downwardly extending legs, material-supporting arms adjustably secured to 35 said legs, a guide carried by the lower ends of said legs, a second guide carried by said right-angle shaped support in the horizontal plane of said first support, a right-angle shaped fixed jaw above said horizontal support, a spring-actuated jaw for cooperating with said fixed jaw in clamping the paper between them, a cover overlying said right-angle shaped support and forming a paper 40 guide in combination with said guide elements, and a yielding roller carried by said right-angle shaped support in position for 45 engagement with the paper and preventing rearward movement thereof.

In witness whereof I hereunto affix my 50 signature.

CLAY R. VINSON.
